UNITED STATES PATENT OFFICE.

FRANK P. ROESCH, OF CHICAGO, ILLINOIS, AND ANDREW M. HUNT, OF NEW YORK, N. Y., ASSIGNORS TO STANDARD STOKER COMPANY, INCORPORATED, A CORPORATION OF DELAWARE.

STOKER.

Application filed May 19, 1924. Serial No. 714,338.

To all whom it may concern:

Be it known that we, FRANK P. ROESCH and ANDREW M. HUNT, both citizens of the United States, and, respectively, residents of Chicago, county of Cook, State of Illinois, and New York, county of New York, State of New York, have jointly invented a new and useful Improvement in Stokers, of which the following is a specification.

10 This invention relates to locomotive or other stokers and its object is to provide a simple and effective means and method for conveying the fuel from the locomotive tender forward to the fire.

15 In apparatus of this character it has heretofore been customary to provide conveying means for feeding the material forward from the tender to the locomotive, then lifting the material to a level above the fire and 20 distributing the fuel to the fire.

25 It is one of the objects of our invention to dispense with the necessity for special lifting apparatus to raise the fuel above the fire and at the same time to provide for continuous and uninterrupted feeding and distribution of the fuel to the fire.

30 It is a further object to provide apparatus of this character which will, if desired, permit the fuel to pass below the mud ring of the boiler and avoid bending or otherwise interfering with the mud ring or other standard parts of the locomotive equipment.

35 Other objects and advantages of the invention will appear from the following specification:

Referring to the accompanying drawings:

Fig. 1 is a side view of our improved stoker, partly in section, taken on the line 1—1 of Fig. 2; also showing fragments of 40 the locomotive and tender. Our improved method may be practiced in this apparatus or in other apparatus.

Fig. 2 is a plan view of the devices of Fig. 1.

45 Fig. 3 is a detail of the driving gears at the rear of coal bin of the tender taken on the line 3—3 of Fig. 2.

Fig. 4 is a section taken on the line 4—4 of Fig. 1.

50 Fig. 5 is a detail showing a modification.

The numeral 1 indicates the rear water leg of a conventional locomotive boiler, provided with a feed door opening 3 and a cab deck is indicated at 5.

The coupling gear between the locomotive and tender is indicated at 7 and upon the frame 9 of the tender there is mounted a conveyor trough 10. Trough 10 contains the rear section 11 of a conveyor screw which is driven by gearing 13, best shown in Fig. 3.

The gearing 13 is driven by a shaft 14, provided with universal joints 15, 17 and 19, and a telescopic joint 20, from a small engine or other source of power 21 carried on the locomotive.

A conventional crusher 23 may be provided at the forward end of the conveyor screw section 11, and the conveyor screw is completed by two additional sections 25 and 27. Section 11 drives section 25 through a universal joint 12, and section 25 drives section 27 through a universal joint 28. Section 25 is provided with a telescopic coupling 26. Sections 25 and 27 are contained in 75 housings 29 and 31, respectively and these housings are provided with universal joints and a telescopic joint of conventional form as illustrated.

At the forward end of the housing 31 we provide an elbow 33. The section 27 of the conveyor screw terminates in the elbow 33 at a point therein, which may be defined as that point which permits the conveyor screw to force the coal as far as possible to the left without causing the coal to pack beneath the screw 27 or to block the easy and smooth flow of the coal around the elbow 33.

The elbow 33 may extend beneath a conventional mud ring 34 of the boiler and be supported on a bracket 37, which may be suitably mounted on the framework of the locomotive. Elbow 33 supports a core tube 39 which rises to the discharge mouth 40, which is surrounded by the protective grate 43 and is provided with the steam jet distributor 41. The distributor comprises a distributor head 50 having substantially radial nozzles or openings 51 which are supplied from a series of pipes 52 as shown. Each of the pipes is provided with an adjustable valve 53 for controlling the supply of steam through the pipe.

The discharge mouth 40, which is at about 105 the level of the bottom of the feed door opening 3, may be in the case of some standard types of locomotives two feet or

more above the mud ring. Thus the core of coal must rise about two feet without arching or choking, which our improved method and apparatus permits. Elbow 33 and tube 39 increase slightly in diameter to ease the flow of the coal toward the mouth 40, which, however, is preferably kept small to facilitate the action of the distributor steam jets and to economize space in the fire box.

10 Coal entering the trough 10 is engaged by the screw section 11 and advanced to the breaker 23 from whence it is carried by screw sections 25 and 27 to the elbow 33. 15 The coal being advanced by the screw section 27 does not normally fill the conveyor tube but is advanced along its lower portion. In accordance with our improved method when the coal leaves the free-end of 20 the screw section 27 it becomes consolidated into a symmetrical stream or core in the elbow and advances around the easy upward curve thereof and through the unobstructed core tube 39 to the mouth 40 for distribution 25 thereof.

The free end of the section 27 of the conveyor screw may be provided with a loosening finger 45, as shown in Fig. 5, which finger consists of a piece of round steel inserted 30 and pinned rigidly in the end of member 27. Finger 45 extends into elbow 33 and is bent as indicated at the extended portion. Finger 45 is desirable for use with some classes 35 of coal to prevent a premature packing of the coal before the coal assumes its straight upward travel in the core tube 39 toward the mouth 40; with other classes of coal this finger 45 is superfluous. Fig. 5 also shows the elbow 33 as formed with longitudinal stator 40 vanes 35, on the lower half thereof to reduce the tendency for rotation of the coal caused by the rotation of section 27 of the conveyor screw in the elbow 33.

The easy curve of the elbow and the slight 45 taper of both elbow and core tube facilitate our thrusting the coal up to the discharge mouth. The coal in the elbow forms itself into a coherent mass which may be moved as a whole up to the mouth 40. While the 50 coherence of the moving core of coal is dependent somewhat upon the amount of moisture which the coal contains, we find that the kinds and grades of coal in use in locomotives contain an amount of moisture that 55 gives the coal a coherence sufficient to enable the same to be lifted through the elbow and core tube. The mass is sufficiently consolidated to enable the coal to be fed forward with substantial uniformity throughout the 60 section of the core and at the same time is sufficiently loose or fluent to prevent excessive friction and to permit the coal to follow the curve of the elbow without packing.

While we have disclosed our invention as 65 applied to one form of locomotive stoker it

will be understood that various modifications may be made in the stoker construction without departing from the spirit of our invention. Thus the rising portion of the stoker conduit may be located outside of the fire box and communicate with the fire box by a horizontal or inclined extension. Furthermore our invention is not limited to stokers of the locomotive type as the same may be applied to stokers for use with marine or 75 stationary boilers.

We claim:

1. The combination with a boiler of an unobstructed conduit without sharp bends curving from horizontal to vertical without sudden changes in its cross-sectional dimensions, said conduit being of substantially the same cross-sectional area throughout, the vertical end of said conduit projecting above the level of the fire and the horizontal end being outside the fire box, a conveying apparatus for delivering coal to the horizontal portion of the conduit and forcing the coal forward through said conduit, and the forward end of said conveying apparatus being spaced 80 from the curved forward wall of said conduit a distance sufficient to prevent packing of the coal in said conduit, and means for projecting the coal delivered through said conduit laterally and radially to the fire 85 through aerial paths.

2. The combination with a boiler, of an unobstructed conduit without sharp bends, curving from horizontal to vertical without sudden changes in its cross sectional dimensions and said conduit being of substantially the same cross-sectional area throughout, the vertical end of said conduit projecting above the level of the fire, and the horizontal end being outside the fire box, a conveying apparatus for delivering fuel to the horizontal portion of the conduit and forcing the fuel forward through said conduit, the forward end of said conveying apparatus being spaced 100 from the curved forward wall of said conduit a distance sufficient to prevent the packing of the coal in said conduit, and distributing jets at the upper end of the vertical portion of the conduit adapted to act on the fuel as it emerges from the conduit.

3. The combination with a boiler of an unobstructed conduit without sharp bends curving from horizontal to vertical without sudden changes in its cross-sectional dimensions, said conduit being of substantially the same cross-sectional area throughout, the vertical end of said conduit projecting above the level of the fire and the horizontal end being outside the fire box, a conveying apparatus which delivers coal to the horizontal portion of the conduit and then forces the coal forward through said conduit as a fluent coherent mass, the forward end of said conveying apparatus being spaced from the curved forward wall of said conduit a distance suffi- 110 115 120 125 130 135

5. The combination with the coal in said conduit, and means for projecting the coal as it is delivered upwardly from said conduit laterally and radially to all parts of the fire through aerial paths. 70
4. The combination with a boiler of an unobstructed conduit without sharp bends curving from horizontal to vertical without sudden changes in its cross-sectional dimensions, 75
10. said conduit being of substantially the same cross-sectional area throughout, the vertical end of said conduit projecting above the level of the fire and the horizontal end being outside the fire box, conveying apparatus which delivers coal in loose condition 80
15. through the horizontal portion of the conduit, then forms said loose coal into a fluent coherent mass in the curved portion of said conduit and forces the fuel while in such condition through said conduit, said conveying apparatus terminating at a point short of that where it would itself be an obstruction to the movement of the coal as controlled by the walls of the conduit, and 85
20. means for projecting the coal delivered through said conduit laterally and radially to all parts of the fire through aerial paths. 90
25. 5. The combination with a fire box of an unobstructed curved conduit without sharp bends extending into said box, said conduit having substantially uniform cross-sectional area throughout, and progressive cross sections of said conduit being of substantially the same form, and said conduit terminating in said fire box above the fire level, means for delivering coal to and forcing the same through said conduit, said means terminating at a point short of that where it would itself be an obstruction to the movement of the coal as controlled by the walls of the conduit, and means for projecting the coal as it is delivered upwardly from said conduit to all parts of the fire through aerial paths. 95
30. 40. 6. The combination with a fire box, a stoker comprising an upwardly curved unobstructed conduit of substantially uniform and relatively small cross section, successive cross sections of said conduit being of substantially the same form and said conduit terminating in a delivery mouth above the fire level, means for supplying coal to said conduit and forcing the same therethrough, and said means terminating short of said unobstructed conduit and a distributor comprising means for directing a plurality of substantially radial fluid jets for forcing the coal as it is delivered upwardly from said conduit to the fire. 100
35. 45. 7. The combination with a fire box, a stoker comprising an upwardly curved unobstructed conduit of substantially uniform and relatively small cross section, successive cross sections of said conduit being of substantially the same form and said conduit terminating in a delivery mouth above the fire level, means for supplying coal to said conduit and forcing the same therethrough, and said means terminating short of said unobstructed conduit and a distributor comprising means for directing a plurality of substantially radial fluid jets for forcing the coal as it is delivered upwardly from said conduit to the fire. 105
40. 50. 8. A locomotive boiler provided with a conventional mud ring, a stoker tube extending horizontally beneath the mud ring and thence turning upwardly to a distributor above the fire level, said tube being unobstructed and having substantially the same cross sectional area and form throughout, a horizontal screw in the horizontal portion of the tube, terminating at a point where the upturned portion commences and stator means at the end of the screw, whereby the coal in the horizontal portion is restrained from rotation by the screw. 110
45. 55. 9. In a locomotive stoker the combination of a horizontal conveyor tube provided with an elbow and an upwardly extending core tube, a screw in the conveyor tube, loosening means mounted at the end of the screw and projecting into the elbow and designed to prevent packing of the coal therein, said upwardly extending tube and elbow forming an unobstructed passage of substantially uniform cross-sectional area and dimensions through which the coal is forced by said screw, and means for projecting the coal as it is delivered upwardly from said conduit to all parts of the fire through aerial paths. 115
50. 60. 10. The combination with a fire box, a stoker comprising an upwardly curved unobstructed conduit of substantially uniform cross section terminating in a delivery mouth above the fire level, progressive cross sections of said conduit being of substantially the same form, a conduit of substantially the same cross section as said first-named conduit and adapted to deliver coal to said first named conduit, a conveyor screw in said second named conduit, the forward end of said screw being spaced from the forward curved wall of said first named conduit a distance sufficient to prevent the packing of coal against said wall, and means for projecting the coal as it is delivered upwardly from said first-named conduit to all parts of the fire through aerial paths. 120
55. 65. 11. The method of conveying coal in the form of an upwardly curved core-shaped flowing stream from a point below the grate of a locomotive fire box to a point above the level of the fire and distributing the same to the fire, the coal being of such a character that it will jam if subjected to pressure in a direction lateral to the flow in excess of a certain amount, which method consists in forming the coal into the upwardly curved 125
60. 70. 65. 75. 80. 85. 90. 95. 100. 105. 110. 115. 120. 125. 130.

- core of substantially uniform cross sectional area and advancing the coal of said core to a point above the level of the fire by substantially uniform pressure applied to the 5 rear end of said core while subjecting said core to a lateral restraint sufficient to maintain said core intact but insufficient to cause jamming of the coal, and projecting said coal when it has reached said point above 10 the level of the fire to all parts of the fire through aerial paths.
12. The combination with a fire box, a stoker comprising a substantially horizontal conduit located below the level of the fire, 15 conveying means within said conduit for conveying coal towards the fire box, an upwardly curving conduit of substantially uniform cross sectional area and free from stationary and moving obstructions, in extension of the horizontal conduit, the two forming a continuous conduit whose delivery mouth is so positioned that the coal delivered therefrom can be laterally and radially projected to all parts of the fire surface in 20 aerial paths, and means for so projecting it.
13. The combination with a locomotive 25 boiler of an unobstructed conduit without sharp bends curving from horizontal to vertical, said conduit being of substantially the same cross-sectional dimensions throughout, 30 the vertical end of said conduit projecting above the level of the fire and the horizontal end being outside the fire box below the level of the locomotive cab deck, conveying apparatus for delivering fuel to the horizontal portion of the conduit and forcing the fuel forward through the conduit, the forward end of said conveying apparatus being spaced from the curved forward wall 35 of said conduit a distance sufficient to prevent the packing of the coal in said conduit, a protecting grate embracing and spaced from the upper portion of said conduit so as to maintain the fire away from said conduit and thereby prevent coking of the fuel 40 in said conduit, and a distributor comprising means for directing a plurality of substantially radial fluid jets for forcing the fuel as it is delivered upwardly from said conduit to the fire.

FRANK P. ROESCH.
ANDREW M. HUNT.
